(57) **CLAIM**

The ornamental design for a handle for treatment cart, as shown and described.

DESCRIPTION

FIG. 1 is a front, left perspective view of a handle for treatment cart showing our new design;

FIG. 2 is another front, left perspective view thereof;

FIG. 3 is a front elevational view thereof;

FIG. 4 is a rear elevational view thereof;

FIG. 5 is a right side elevational view thereof, the left side elevational view being a mirror image;

FIG. 6 is a top plan view thereof; and,

FIG. 7 is a bottom plan view thereof.

The broken lines within the handle depict portions of the handle for treatment cart that form no part of the claimed design. The broken lines showing a treatment cart in FIG. 1 depict environment and form no part of the claimed design.

1 Claim, 4 Drawing Sheets
